UNITED STATES PATENT OFFICE

159,800

PRINTING TELEGRAPH APPARATUS
CABINET

Gilbert C. Gettelman, Hartford, Wis., assignor to
Teletype Corporation, Chicago, Ill., a corpora-
tion of Delaware

Application January 26, 1950, Serial No. 7,509

Term of patent 14 years

(Cl. D26—14)

To all whom it may concern:

Be it known that I, Gilbert C. Gettelman, a citizen of the United States, residing at Hartford, State of Wisconsin, have invented a new, original, and ornamental Design for Printing Telegraph Apparatus Cabinet, of which the following is a specification, reference being had to the accompanying drawing, forming a part hereof.

Fig. 1 is a front isometric view of the printing telegraph apparatus cabinet taken at one corner thereof; and

Fig. 2 is a rear isometric view taken at a corner thereof.

What is claimed is:

The ornamental design for a printing telegraph apparatus cabinet, substantially as shown.

GILBERT C. GETTELMAN.
